CLAIM

The ornamental design for a sliding case, as shown and described.

DESCRIPTION

FIG. 1 is a front top and right side perspective view of a sliding case in a closed condition in accordance with my invention;

FIG. 2 is a rear, bottom and left side perspective view thereof;

FIG. 3 is a top plan view thereof;

FIG. 4 is a rear view thereof;

FIG. 5 is a bottom plan view thereof;

FIG. 6 is a left side view thereof;

FIG. 7 is a perspective view thereof as in FIG. 1 except with the sliding case of my invention shown in an open condition; and,

FIG. 8 is a longitudinal view across lines 8—8 of FIG. 7 revealing the interior facing side of the rear side and which is identical/symmetric to the interior facing side of the front side.
